REFRIGERATING SYSTEM OF THE INERT GAS TYPE

Floyd E. Dixon, Los Angeles, Calif.

Application October 6, 1943, Serial No. 505,210

1 Claim. (Cl. 62—119.5)

1

The invention relates to refrigeration, and particularly to evaporators for use in domestic refrigeration enclosures.

The primary object of the invention is the provision of an apparatus of this character wherein the same has three continuous cycles involving the activity of ammonia, distilled water and helium or hydrogen gas, so that through such operation these cycles of mediums automatic refrigeration is had by the apparatus with efficiency.

Another object of the invention is the provision of an apparatus of this character wherein the structure is of novel arrangement and is thoroughly effective for the automatic refrigeration activity in the working thereof.

A further object of the invention is the provision of an apparatus of this character which is simple in its construction, thoroughly reliable and efficient in operation, and inexpensive to manufacture and install.

With these and other objects in view, the invention consists in the features of construction, combination and arrangement of parts as will be hereinafter more fully described in detail, illustrated in the accompanying drawings, which discloses the preferred embodiment of the invention and pointed out in the claim hereunto appended.

In the accompanying drawings:

Figure 1 is an elevation of the apparatus constructed in accordance with the invention, the refrigeration enclosure being shown fragmentarily, that is to say the evaporator coils thereof.

Figure 2 is an enlarged vertical sectional view through the generator and separator structure per se.

Figure 3 is a sectional view taken on the line 3—3 of Figure 2, looking in the direction of the arrows.

Figure 4 is a detail plan view partly broken away of the heat exchanger and condenser of the apparatus.

Figure 5 is a fragmentary detail sectional view taken on the line 5—5 of Figure 4, looking in the direction of the arrows.

Figure 6 is a plan view partly in section and partly broken away of the heat exchanger coil of the apparatus, and

Figure 7 is a detail fragmentary sectional view taken on the line 7—7 of Figure 1.

Similar reference characters indicate corresponding parts throughout the several views in the drawings.

Referring now to the drawings wherein like reference characters indicate corresponding parts

2

the refrigerator of this invention includes a section A of an enclosure or cabinet such as a refrigerator and refrigerating apparatus B. The apparatus includes a generator 10 having an inclined tubular chamber 11 suspended above the upper end with the interior of the chamber 11 communicating with a chamber 12 in the generator through a supporting tube as shown in Figure 2. An inner tube 13 extends from a reduced area in the lower part of the chamber 12 through the supporting tube and carries a condensate tray 14 at the upper end which is held in an inclined position. The high end of the chamber 11 is provided with a connection 15 through which ammonia vapor, expelled from an ammonia water solution in the generator by the application of heat, passes to an ammonia vapor chamber 16 associated with a condenser 17.

20 The condenser is formed with a spiral inner tube 18 in which the ammonia is condensed to liquid and the tube is surrounded by a spiral outer casing for the inert gas which enters through a tube 19. One end of the inner tube 18 communicates with the interior of the ammonia vapor chamber 16 and the other end is connected to an upper coil 20 of an evaporator by a tube 21 having a trap therein. The tube 19 connects the outer casing of the condenser to the upper spiral coil 20 of the evaporator through the tube 21. The coil 20 is connected by a tube 22 to a lower spiral coil 23 of the evaporator, and the lower coil is provided with a connection 24 having two branches 25 and 26. The connection 25 extends 25 to an inert gas chamber 27, and the connection 26 extends to a water and ammonia solution tank 28. An inert gas return connection 29 is provided from the end of the large coil of the outer casing of the condenser 17 to the solution tank 28.

30 The tank 28 is associated with a spiral absorber coil 30 which is positioned above the tank and a similar coil 31 is positioned below the tank. The coil 30 is connected to the solution tank 28 at the point 32 and the opposite end is connected to the coil 31 by a connection 33.

35 The ammonia is washed out of the fluid in the coil 30 by water entering through the connection 33, and the liberated inert gas passes through the connection 34 to the inert gas chamber 27.

40 The lower coil 31 is connected by a tube 35 to the outer passage of a liquid heat exchanger 36 which has an inner coil 37, one end of which is connected by a pipe 38 to the chamber 12 of the

generator 10, and the other end being connected by a pipe 39 to the tank 28. The other end of the outer passage of the liquid heat exchanger is connected by a tube 40 to the lower end of the inclined tubular chamber 11 and a cross connection 41 is provided between the sections of the outer passage. A charging or refilling plug 42 is provided in the connection 34 between the absorber coil 30 and the inert gas chamber 27. The system contains a refrigerant fluid such as ammonia, an absorption liquid such as water, and an inert gas such as hydrogen or helium.

Heat is applied to the generator 10 by a burner or heater 43 and the heat expels ammonia vapor from solution. The ammonia vapor flows through connection 15 into chamber 16 and into condenser 17. Water vapor is condensed out of the ammonia vapor in the rectifier chamber 16, and the ammonia vapor is condensed to liquid in the condenser 17. Liquid ammonia flows from the inner tube 18 of the condenser 17 through the tube 21 to the upper section 20 of the evaporator. Liquid ammonia flows downward in the evaporator coils and evaporates and diffuses into the hydrogen, producing a refrigerating effect in the chamber or cabinet A.

Hydrogen enters the lower end of the evaporator coil 23 through the tube 24. Rich gas flows from the upper end of the evaporator through the tube 21 in the opposite direction to that of the liquid ammonia, and being stopped by a trap in the tube 21 enters the outer casing of the condenser 17 through a tube 19. The inert gas then returns to the solution tank 28 through the pipe 29.

Weakened absorption solution flows from the generator 10 through pipe 40, the outer passage of the liquid heat exchanger 36, and pipes 35, 31, and 33 into the absorber.

In the absorber, weakened absorption solution absorbs ammonia vapor out of the inert gas. Enriched absorption solution flows through tube 39, the inner passage of liquid heat exchanger 36, and tube 38 to chamber 12 of the generator. Solution is raised from the chamber 12 of the generator through the vapor lift tube 13 to the tray 14 in the inclined tubular chamber 11 wherein water is removed from the ammonia and the condensate returns to the generator and outer passage of the liquid heat exchanger.

Weak or inert gas flows from the upper coil 30 of the absorber through the connection 34 to the inert gas chamber 27, and from this chamber to the evaporator through the connection 25 and tube 24.

The cool mixture of ammonia and helium or hydrogen gas passes around the outer passage of the condenser 17, back to the solution tank 28, and up through the absorber coil 30.

Water condensate in the ammonia vapor chamber 16 passes downward to the chamber 11 through the connection 15.

It will be understood that modifications may be made in the design and arrangement of the parts without departing from the spirit of the invention.

The cool mixture of ammonia and helium or hydrogen gas passes through the condenser coil 17 back to the solution tank 28 and up through the absorber coil 30, where the gas is washed free of ammonia.

The inclination of the separator chamber 12 and the trough 14 directs the water, separated from the ammonia gas, to the lower ends of the same for discharge downwardly through the outlet pipe 40 and its return to the jacket 36, of the heat exchanger 37, while allowing the ammonia gas to pass from the higher end of the chamber 12 and upwardly through the conduit 15 to the vapor chamber 16.

What is claimed is:

A refrigerating system including a generator having an inclined tubular chamber suspended by a vertically disposed tube above the upper end thereof with a condensate tray in the tubular chamber suspended from the generator by a tube extending through the vertically disposed tube, a condenser having an ammonia vapor chamber in combination therewith and comprising a spiral inner tube in which ammonia is liquified and an outer casing surrounding the inner tube, a connection from the inclined tubular chamber of the generator to the ammonia vapor chamber, an evaporator having opposed spiral tubular coils, a tube connecting the inner end of the spiral inner tube of the condenser to the upper end of the evaporator, an inert gas chamber, an absorber having a solution tank associated therewith, a branch connection from the evaporator to the inert gas chamber and solution tank of the absorber, a connection from the evaporator to the outer casing of the condenser, an inert gas return connection from the outer casing of the condenser to the said solution tank, a connection from the solution tank to the upper absorber coil wherein ammonia is washed out of the fluid by water, a connection from the said upper coil of the absorber to the inert gas chamber, a heat exchanger having an inner tube and an outer passage, a connection from the solution tank to the inner tube of the heat exchanger, a connection from the inner tube of the heat exchanger to the generator, a connection from the lower end of the inclined tubular chamber of the generator to the outer passage of the heat exchanger, and a connection from the outer passage of the heat exchanger to the upper coil of the absorber.
